UNITED STATES PATENT OFFICE.

TOM JOSEPH SALES, OF SAN FRANCISCO, CALIFORNIA.

RETURNABLE ENVELOP.

No. 918,093.

Specification of Letters Patent.

Patented April 13, 1909.

Application filed December 16, 1907. Serial No. 406,599.

To all whom it may concern:

Be it known that I, TOM J. SALES, a citizen of the United States, residing at San Francisco, in the county of San Francisco and State of California, have invented a new and useful Returnable Envelop, of which the following is a specification in such full and clear terms as will enable those skilled in the art to construct and use the same.

10 The object of this invention is to make a return envelop for the use of railways, express companies and the Post Office Department or other large businesses where it is desired to send out certain matter and have a 15 reply to the letter sent out returned at once with the desired information.

Another object of the invention is to make an envelop that will save the cost of one envelop and be of the same service as two 20 where it is possible to use the envelop for the return of matter that has been sent out in it, as in the cases mentioned above.

Another object of the invention is to provide means for sealing the envelop with the 25 smallest possible amount of the adhesive, said adhesive being placed on the envelop in only three places, and those places are all on the same side of the envelop blank as the same is cut from the sheet thus making it 30 very easy to gum.

Other objects of the invention will appear as the description proceeds.

In the drawings in which the same numeral is applied to the same parts throughout, Figure 1 is a perspective view of the cut blank, Fig. 2 is a side elevation of the blank folded into an envelop, and Fig. 3 is a vertical sectional view of the envelop looking from one end.

40 The envelop is formed with the body portion 1, the bottom flap 2, the end flap 3, and the securing flap 4 all the latter of which are secured to the body 1. In addition the flap 3 has a sealing flap 6 and two securing tabs 8 and 9, and the flap 2 has a securing flap 5 on one end. The envelop is then folded with the flap 3 between the body portion 1 and the bottom flap 2, the tabs 8 and 9 projecting through the slots in the bottom of the envelop. The two compartments formed in this way are then sealed at the ends by means of the securing flaps 4 and 5, the latter

being gummed to the body 1 and the former to the bottom flap 2.

It will be noted that the result of the above 55 construction is to form an envelop having two pockets with only the material necessary for one and one-half ordinary envelops. The envelop may be sealed with no more gum than the common envelops, since there are 60 only three gummed places. The envelop is mailed in the first place, when the sealing flaps 4 and 5 have been secured, by placing the letter in the compartment formed by the bottom flap 2 and the end flap 3, the sealing 65 flap 6 being turned down so that its gummed side is out, the tabs 8 and 9 being used to seal the letter. The letter having reached its first destination the tabs are torn off and the letter is placed in the compartment formed 70 by the body 1 and the end flap 3, the sealing being accomplished this time by the use of the remaining gum on the flap 6, which is attached to the body portion 1, since when the letter was sent out in the first place only 75 the small amount of gum at the points 11 and 12 was used.

Since money is usually sent only one way the envelop may be used for that purpose when the tabs 8 and 9 are secured to the sealing flap 6, but should it be desired to make the envelop secure on both trips a little mucilage may be placed on the bottom of the flap 3 to prevent its removal from the envelop, but in any event it is almost sure that 85 the envelop will be torn should it be tampered with.

Having thus described my invention in such full and clear terms as will enable those skilled in the art to make and use the same 90 what I claim as new and desire to secure by Letters Patent of the United States is as follows:

1. In a return envelop, a body having a bottom flap secured thereto and a slot along 95 the line of fold of the body and bottom flap, an end flap secured to the end of the body and having a tab on one side and a sealing flap on the other side, and tabs to secure the body to the bottom flap at each end thereof. 100

2. In a return envelop, a body, an end flap having tabs on one edge and a sealing flap on the other edge, a bottom flap secured to one of the edges of the body and having slots

along the line of fold of the body and bottom flap to register with the tabs on the end flap when the same is folded, a sealing tab on one end of the bottom flap and a sealing tab on the opposite end of the body all the sealing flaps having gum on the same side when the envelop blank is flat.

In testimony whereof I have set my hand this 7th day of December A. D. 1907, in the presence of the two subscribed witnesses.

TOM JOSEPH SALES.
